CENTRAL STEEL COMPANY, OF MASSILLON, OHIO, A CORPORATION OF OHIO.

HOT TOP FOR INGOT-MOLDS.

1,398,874.

Specification of Letters Patent. Patented Nov. 29, 1921.

Application filed October 30, 1919. Serial No. 334,492.

To all whom it may concern:

Be it known that we, THOMAS McNALLY and WILLIAM S. ORR, citizens of the United States, residing at Massillon, in the county 5 of Stark and State of Ohio, have invented a new and useful Hot Top for Ingot-Molds, of which the following is a specification.

This invention has reference to hot tops 10 for ingot molds, and its object is to provide a hot top having relatively long life, such hot top being designed to prevent piping in the ingots.

In accordance with the invention the hot top, which is arranged to rest on the upper 15 end of the mold, is constructed to retain a suitable mass of molten metal above and in position to feed into the mold as cooling progresses, and provision is made whereby the metal in the hot top retains its heat and 20 molten condition after the metal in the body of the mold has cooled, whereby the liability of the formation of piping is reduced to a minimum.

To provide for the retention of the heat in 25 the hot top with economical production of such hot top, the structure is made in the form of a hollow casting with the usual core, but in the use of the hot top, the core is retained, such core being customarily of 30 sand or casting loam, and such core serves as a heat insulator so situated that warping or cracking of the hot top is avoided, and such hot top may be used repeatedly without harmful effect upon it.

The invention will be best understood 35 from a consideration of the following detailed description taken in connection with the accompanying drawings forming part of this specification, with the understanding, 40 however, that the invention is not confined to any strict conformity with the showing in the drawings, but may be changed and modified so long as such changes and modifications mark no material departure from the 45 salient features of the invention as expressed in the appended claims.

In the drawings,

Figure 1 is a vertical section through the upper end of an ingot mold, with the hot top 50 applied in section and in the same plane as the mold;

Fig. 2 is an elevation of a hot top at right angles to the showing of Fig. 1;

Fig. 3 is a section through the hot top 55 removed from the mold with the section taken

on a plane at right angles to that of Fig. 1;

Fig. 4 is a plan view of the hot top;

Fig. 5 is an elevation of a modified form of a hot top;

Fig. 6 is a section on the line 6—6 of 60 Fig. 5;

Fig. 7 is a section on the line 7—7 of Fig. 5.

Referring to the drawings, there is shown in Fig. 1 an ingot mold 1 which may be of 65 common construction and therefore requires no special description. Such mold is used in an upright position, wherefore that part of the mold appearing at the top in Fig. 1 constitutes the upper end of the mold. 70

There is also provided a hot top 2 conforming in cross sectional shape to that of the upper end of the mold 1, which shape in the particular showing of the drawings is approximately rectangular. 75

The hot top is provided with inner walls 3, outer walls 4, a closed hollow flange 5 at the lower edge which, in the showing of Fig. 1 and associated figures, is of sufficient length to enter for a short distance into the 80 upper end or mouth of the mold 1. The top of the space between the walls 3 and 4 is closed by a wall 6, except that certain openings 7 are left. These openings are provided to permit the escape of the gases arising 85 within the chamber defined by the walls 3, 4, 5, 6, during the manufacture of the hot top. When the hot top is completed, these openings may be plugged or hermetically sealed by closures 8. Furthermore, the space 90 between the walls 3 and 4 is bridged at intervals by connecting members 9 serving as braces for the walls.

When such hot top is completed, it is hollow so far as the metal portion thereof is 95 concerned, but is filled with heat insulating material. Either the original core, which has heat insulating qualities, may be retained, or some other suitable material may be substituted for it. 100

To facilitate the manipulation of the hot top, handles 11, which may be of web and flange construction, are formed on opposite sides of the hot top.

The flange 5 is of suitable length to extend sufficiently into the top of the mold to properly retain the hot box and is beveled on the outer side so that it will freely enter the top of the mold. Where the flange 5 extends from the bottom of the hot top, a 110

shoulder 12 is formed, and this shoulder, where resting upon the top of the mold, has a groove 13 therein so that fire clay 13^a, or other heat resisting material, to the depth of about one half an inch, may be placed on the upper wall of the mold and fill the groove and thus seal the joint between the shoulder 12 and the top of the mold 1, and thereby prevent formation of fins due to the exudation of molten metal which, when the structure is in operation, rises into the hot top above the lever of the top of the mold. When the hot top is removed, the seal may be easily broken. The heat insulating material 13^a may be placed in the groove before the hot top is set on the mold.

In Figs. 5, 6 and 7, the structure is similar to that of Fig. 1 and associated figures, with the difference that, instead of the hollow flange 5, there is provided a shorter, solid, flange 14 of sufficient length to enter a suitable distance into the upper end or mouth of the mold 1.

When the hot top is in operation, with the level of molten metal reaching for an appropriate distance above the bottom of the hot top and above the top of the mold, radiation of heat from the hot top is retarded by the heat insulating qualities of the core within the hot top. Moreover, the core is of a nature to resist the effects of heat, wherefore the hot top is not subjected to great variations of heat in different portions of it, with the result that warping is, to a large extent, if not entirely, avoided. This contributes markedly to the lasting qualities of the hot top, and experience has shown that the life of the hot top is greatly prolonged and each hot top may be repeatedly used, wherefore the economy of use of the hot top is pronounced. Because of the heat retaining qualities of the hot top due to the inclosed sand core employed in the casting operation and permanently retained, or other suitable material substituted for it the production of pipes in the ingots is very nearly eliminated.

Experience with this hot top has demonstrated the fact that it will give a greater percentage of solid steel from the amount

poured than any other device known. Hot tops employing fire clay linings can only be used for one pouring, whereas the hot top of the present invention is capable of almost an indefinite period of use.

55

What is claimed is:

1. A hot top for ingot molds, comprising a collar of a size to rest upon and be supported by the top of the mold, said collar having a passage therethrough leading to the interior of the mold for access to said interior, and also having inner, outer, top and bottom walls defining a closed chamber, and heat insulating material located in said chamber and comprising the core material employed in the casting operation.

2. A hot top for ingot molds having inner and outer walls and a centrally located passage through the hot top for communication with the interior of the mold, the inner and outer walls being closed and defining a chamber filled with the core material employed in the casting of the hot top, the inner wall of the hot top having a depending flange for entrance into the upper end of the mold.

3. A hot top for ingot molds provided with inner, outer, top and bottom walls defining a chamber and filled with heat insulating material, and connecting members or braces between the inner and outer walls of the hot top.

4. The method of producing hot tops for ingot molds, consisting in providing a core of heat insulating material and casting inner, outer, top and bottom walls about said core, with preliminary openings in the upper wall to permit the escape of moisture and gases and subsequently sealing the preliminary openings to retain the core material within the hot top.

In testimony that we claim the foregoing as our own, we have hereto affixed our signatures in the presence of two witnesses.

THOMAS McNALLY.
WILLIAM S. ORR.
